United States Patent Office

Des. 229,441

Patented Nov. 27, 1973

229,441

HORIZONTAL REFUSE BALER

Jay R. Guhl, San Leandro, Calif., assignor of a fractional part interest to W. Dean Park

Filed Dec. 27, 1971, Ser. No. 212,857

Term of patent 14 years

Int. Cl. D15—99

U.S. Cl. D55—1 B

Fig. 3

Fig. 1

Fig. 2

FIG. 1 is a side elevation of a horizontal refuse baler showing my new design;

FIG. 2 is a plan view of the baler;

FIG. 3 is an end elevation of the baler;

FIG. 4 is an end elevation of the baler taken from the opposite end from FIG. 3; and

FIG. 5 is a side elevation of the baler taken from the opposite side from FIG. 1.

I claim:

The ornamental design for a horizontal refuse baler, as shown.
